UNITED STATES PATENT OFFICE

2,659,734

DEHYDROGENATION OF COUMARANES

Theodore A. Geissman, Los Angeles, Calif.

No Drawing. Application July 30, 1951.
Serial No. 239,375

3 Claims. (Cl. 260—346.2)

1

This invention relates to a new method of dehydrogenation of coumaranes and substituted coumaranes to prepare coumarones and substituted coumarones.

This invention is useful in that it comprises a convenient, practical and efficient method of preparing coumarones from coumaranes involving, essentially, a process whereby the coumarane is dehydrogenated. The particular novelty and usefulness of this invention resides in the fact that it provides greater yields of the dehydrogenated coumarone than are ordinarily obtained with the use of well-known, common methods of dehydrogenation, such as the use of catalysts like platinum, palladium on carbon, Raney nickel and others, at elevated temperatures. Further, the method of this invention possesses additional advantage in that materials and apparatus necessary to effect the process are less expensive and easier to handle, using ordinary laboratory techniques.

The compounds which are the products of the method of this invention will find utility as intermediates, and more particularly, as intermediates in the preparation of compounds having physiological activity, such as khellin and visnagin.

The method according to this invention comprises, generally speaking, treatment of a coumarane-type compound with a halogen-containing reagent which is capable of initiating a free-radical halogen attack upon the coumarane to effect halogenation of that coumarane, replacing one of the hydrogen atoms of the dihydro compound. The halo derivative is then dehydrohalogenated in the presence of a suitable, basic reagent, preferably a tertiary amine, to effect unsaturation of the 2,3 position of the compound.

The exact position of the halogen atom in the halo-coumarane structure resulting from the treatment of the coumarane with N-halosuccinimide is not definitely established, although it is believed to occur in the 2-position. It is to be noted that the position of the halogen atom is not material to the spirit nor the operation of this invention since, as it will be appreciated, the subsequent dehydrohalogenation eliminating HX collectively from the 2 and 3-positions in the coumarane to form the 2,3-unsaturated coumarone is effected with equal ease from either the 2-halo or the 3-halo isomer. It is, therefore, not intended that this invention shall be so limited as to exclude the use of either isomer or even a mixture of both isomers.

The method in accordance with this invention

as applied to exemplary compounds is illustrated by way of example in the following scheme, in which R¹, R², R³, R⁴ may be selected from the group consisting of hydrogen, lower alkoxy, lower acyl, lower acyloxy radicals and any two adjacent of which may together comprise a pyrone radical, and X is a halogen which preferably may be selected from the group consisting of chlorine and bromine:

By way of further example, the method in accordance with this invention has been found to work in a highly satisfactory manner when applied to any unsubstituted coumarane and coumaranes substituted in the 4, 5, 6 or 7 position by lower alkoxy, lower acyl, and lower acyloxy radicals as well as to dihydrofuranochromones. As more particularly illustrative of starting materials may be mentioned the following compounds:

As specifically illustrative of the halogen-containing reagents capable of initiating a free-radical halogen attack, may be mentioned, N-bromophthalimide, N-bromacetamide and halogen derivatives of succinimide, such as N-bromo-

succinimide and N-chlorosuccinimide, whose structures appear below:

As specifically illustrative of the bases which may be utilized to effect the dehydrohalogenation of the halocoumarane are tertiary amines as for example, dimethylaniline, collidine, quinoline and pyridine.

The following examples will further serve to illustrate the method in accordance with this invention:

EXAMPLE 1

Preparation of 6-acetylvisnaginone

1 g. of 4-methoxy-5-aceto-6-acetoxycoumarane (dihydrovisnaginone acetate) was treated with slightly more than an equimolar portion of N-bromosuccinimide and a trace of benzoyl peroxide in boiling carbon tetrachloride solution. The completion of the reaction within a few minutes was indicated by the formation of succinimide and a nearly colorless reaction mixture. Filtration and evaporation resulted in the isolation of the crude bromodihydrovisnaginone acetate. The bromo derivative was then treated with an excess of dimethylaniline and was heated on a steam bath. The reaction mixture was then poured into dilute hydrochloric acid and extracted with ether to yield the 6-acetylvisnaginone.

The 6-acetylvisnaginone product was then saponified by heating it with an aqueous solution of potassium hydroxide. Acidification of the basic solution precipitated visnaginone, which melted at 109° C., and was identical in every respect with visnaginone obtained by the degradation of visnagin.

EXAMPLE 2

Preparation of 6-acetylkhellinone

3.86 g. of dihydrokhellinone acetate (4,7-dimethoxy-5-aceto-6-acetoxycoumarane), 2.55 g. of N-bromosuccinimide and a trace of benzoyl peroxide were refluxed in 150 g. of carbon tetrachloride for 5 minutes. The succinimide was removed by filtration and evaporation isolated an oil. The oil was heated with 80 g. of purified dimethylaniline for 3 hours at 210° C. After cooling, the solution was added to ether and extracted several times with 3 N sulfuric acid. The ether solution was evaporated and the residue was recrystallized from alcohol and water to give khellinone acetate (4,7-dimethoxy-5-aceto-6-acetoxycoumarane) which melted at 74-75° C.

15 As specifically illustrative of the utility of this invention is the following, in which khellinone acetate is converted to khellinone, which in turn may be utilized to prepare khellin, a compound having physiological activity, as follows:

20

EXAMPLE 2 (continued)

40

The khellinone acetate prepared above was saponified to prepare khellinone by treating with a solution of 10 g. of potassium hydroxide and 150 g. of aqueous (1:1) methanol and heating on the steam bath for 30 minutes. Evaporation of the methanol was followed by addition of more water, and the solution was washed with ether and acidified. Ether extraction of the mixture followed by evaporation of the ether gave a slowly crystallizing oil. Purification of the khellinone was effected by a chromatographic technique using a column of alumina and benzene solution. The eluate contained khellinone which upon evaporation provided crystals melting at 92-94° C.

55 The conversion of the khellinone to khellin was effected by treating the khellinone with ethyl acetate in the presence of metallic sodium and heating the mixture on the steam bath for five hours. Methanol is then added to the reaction mixture to destroy traces of excess metallic sodium and the mixture is diluted with water, followed by acidification by acetic acid. A brown oil gradually solidifies, and is redissolved in a 60 large quantity of light petroleum boiling from 70 to 100° C. Distillation of the light petroleum leaves a saturated solution which upon cooling deposits a crystalline material. Recrystallization several times from benzene-light petroleum provides small yellow prisms melting at 105° C. Ring closure of the diketone so obtained is effected by boiling the acetoacetyl compound in alcohol solution acidified with 4 drops of concentrated hydrochloric acid. Cooling isolates crystalline khellin melting at 153° C.

5

EXAMPLE 3

Preparation of 4,6-dimethoxycoumarone

4,6-dimethoxycoumarone was prepared from 4,6-dimethoxycoumarane by treating with an equimolar quantity of N-chlorosuccinimide and a trace of benzoyl peroxide to prepare the chlorocoumarane. Heating of this material on a steam bath with an excess of collidine prepared the coumarone, using a procedure identical with that described in Example 1 above.

EXAMPLE 4

Preparation of 5-acetyl-6-acetoxycoumarone

A mixture of 976 mg. of 5-acetyl-6-acetoxycoumarane, 840 mg. of N-bromosuccinimide, a trace of benzoyl peroxide and 40 ml. of carbon tetrachloride was refluxed for 75 minutes. The mixture was then cooled and filtered and the filtrate was evaporated in an air stream. The crystalline residue was refluxed with 15 ml. of dimethylaniline for 3 hours, and after extraction, evaporation and recrystallization there was obtained the product, 5-acetyl-6-acetoxycoumarone.

The product was characterized as the 6-hydroxy derivative which was obtained upon hydrolysis with an alcoholic potassium hydroxide solution. The crude, semi-crystalline product resulting was sublimed at 90-100° C./5 mm. and was recrystallized from dilute methanol to provide 5-acetyl-6-hydroxycoumarone melting at 94-95.5° C.

EXAMPLE 5

Preparation of 2-methyl-(4',5',6,7)-furanochromone-4

A mixture of 800 mg. of N-bromosuccinimide, 800 mg. of the dihydrofuranochromone and a few mg. of benzoyl peroxide was refluxed with 35 ml. of carbon tetrachloride. Treatment of the refluxed product with dimethylaniline yielded a crude crystalline material which upon recrystallization from methanol melted at 175-181° C.

10

6

EXAMPLE 6

Preparation of visnagin

2-methyl-5-methoxy-2',3'-dihydro-(4',5',6,7)-furanochromone-4 was halogenated with N-bromosuccinimide in a manner identical with that described in Example 5 above. Dehydrohalogenation with dimethylaniline of the bromo derivative so prepared yielded crystalline visnagin which was purified by recrystallization to provide a product melting at 142-143° C.

EXAMPLE 7

Preparation of khellin

2-methyl-5,8-dimethoxy-2',3'-dihydro-(4',5',6,7)-furanochromone-4 was brominated by N-bromosuccinimide and the bromo derivative so prepared was dehydrohalogenated with dimethylaniline in a manner identical with that described for Example 5. Recrystallization of the crude crystalline product yielded khellin melting at 152-153° C.

What is claimed is:

1. The method of forming the corresponding coumarone from a coumarane having the following formula:

65

where R¹, R², R³, R⁴ are selected from the group consisting of hydrogen, lower alkoxy, lower acyl, and lower acyloxy radicals and any adjacent two of which comprise together a pyrone radical, which comprises subjecting the coumarane to a free radical halogen attack to form a halocoumarane and reacting the thus formed halocou-

marane with a tertiary amine base to form a coumarone.

2. The method of preparing 6-acetoxy-5-aceto-4-methoxycoumarone which comprises reacting 6-acetoxy-5-aceto-4-methoxycoumarane with N-bromosuccinimide and reacting the bromocoumarane thus formed with dimethyl-aniline.

3. The method of preparing 6-acetoxy-5-aceto-4,7-dimethoxycoumarone which comprises react-

ing 6-acetoxy-5-aceto-4,7-dimethoxycoumarane with N-bromosuccinimide and reacting the bromocoumarane thus formed with dimethyl-aniline.
